CLAIM

The ornamental design for a product container, as shown and described.

DESCRIPTION

FIG. 1 is a right front perspective view of a first embodiment of a product container.

FIG. 2 is a left rear perspective view of the product container shown in FIG. 1.

FIG. 3 is a front view of the product container shown in FIG. 1.

FIG. 4 is a right side view of the product container shown in FIG. 1, the left side view being a mirror image thereof.

FIG. 5 is a rear view of the product container shown in FIG. 1.

FIG. 6 is a top view of the product container shown in FIG. 1.

FIG. 7 is a bottom view of the product container shown in FIG. 1.

FIG. 8 is a cross-sectional view of the product container shown in FIG. 3, taken along line 8-8 in FIG. 3.

FIG. 9 is a right front perspective view of a second embodiment of the product container.

FIG. 10 is a front view of the product container shown in FIG. 9.

FIG. 11 is a right side view of the product container shown in FIG. 9, the left side view being a mirror image thereof.

FIG. 12 is a rear view of the product container shown in FIG. 9.

FIG. 13 is a top view of the product container shown in FIG. 9.

FIG. 14 is a bottom view of the product container shown in FIG. 9.

FIG. 15 is a cross-sectional view of the product container shown in FIG. 10, taken along line 15-15 in FIG. 10.

FIG. 16 is a right front perspective view of a third embodiment of the product container.

FIG. 17 is a front view of the product container shown in FIG. 16.

FIG. 18 is a right side view of the product container shown in FIG. 16, the left side view being a mirror image thereof.

FIG. 19 is a rear view of the product container shown in FIG. 16.

FIG. 20 is a top view of the product container shown in FIG. 16.

FIG. 21 is a bottom view of the product container shown in FIG. 16; and,

FIG. 22 is a cross-sectional view of the product container shown in FIG. 17, taken along line 22-22 in FIG. 17.

The broken lines in the cross sections of the figures show a boundary for an unclaimed area. The dot-dash lines on the drawings are shown for the purpose of illustrating portions of the Product Container and form no part of the claimed design.
